(74) Attorney, Agent, or Firm — Bayramoglu Law Offices LLC

(57) **CLAIM**

The ornamental design for a bearing restrictor nut, as shown and described.

DESCRIPTION

FIG. 1 is a front perspective view of a bearing restrictor nut showing our new design;

FIG. 2 is a rear perspective view thereof;

FIG. 3 is a perspective view thereof in a used state;

FIG. 4 is a front view thereof in the used state;

FIG. 5 is a front view thereof; and,

FIG. 6 is a rear view thereof.

The broken line showing of a bearing in FIG. 3 and FIG. 4 is for the purpose of illustrating the environmental structure and forms no part of the claimed design.

1 Claim, 6 Drawing Sheets
